UNITED STATES PATENT OFFICE.

MILEY W. THOMAS AND PAUL H. HAMILTON, OF CLEVELAND, OHIO, ASSIGNEES TO THE SANDS MANUFACTURING COMPANY, OF CLEVELAND, OHIO, A CORPORATION OF OHIO.

CONTROL MECHANISM.

Application filed April 6, 1925, Serial No. 21,164.

This invention relates to an apparatus for heating a fluid, such as water, to any desired degree of temperature for use for varying purposes; more particularly the invention 5 relates to the automatic control or shut-off of the medium that is utilized to heat the water, whereby waste thereof is prevented and danger of fire and explosion avoided. For illustrative purposes, the invention is 10 shown in connection with a water heater of the storage type; but obviously it may be applied to other forms or types of construction.

The invention is, in the illustrated embodiment thereof, associated with a supply pipe for the combustion medium, in which is interposed a valve and thermostatic means, that are acted upon by the rise and fall of the temperature in the fluid tank, to control 20 the valve and its object is to provide means for shutting off the supply of the combustion medium in the event the pilot goes out, either by accident or otherwise.

Another object of the invention is to provide 25 a control means for the combustion medium having improved means associated with the pilot burner and through which the heat of the burner is conducted to maintain the control means in inoperative position 30 without causing or permitting the accumulation of carbon on the burner; so that the pilot burner will burn continuously and thus insure the lighting and re-lighting of the main burner or heating means.

Another object of the invention is to provide 35 an improved control means for a combustion medium, wherein certain elements thereof are enclosed within a casing forming a unitary part of the thermostatic and valve 40 mechanisms to protect them and to insure their positive operation.

Other objects of the invention will be apparent to those skilled in the art to which our invention relates from the following description taken in connection with the accompanying drawings, wherein

Fig. 1 is an elevation of an apparatus embodying our invention.

Fig. 2 is an enlarged fragmentary sectional view, the parts being shown in operated position.

Fig. 3 is a section on the line 3-3 of

Fig. 2.

Fig. 4 is a section on the line 4-4 of

Fig. 2.

Fig. 5 is a view on the line 5-5 of Fig. 2 looking in the direction of the arrows.

Fig. 6 is a fragmentary view showing the elements in their positions when the pilot 60 burner is lighted.

In the drawings, 1 indicates a tank or container for holding the fluid, such as water, to be heated. The tank 1 may be supported on one or more legs 1*. 2 indicates a heating 65 means. In the form of construction shown, the heating means 2 is disposed at one side of the tank 1, but it is obvious that it may be mounted below the tank. The heating means 2 is preferably of a construction capable of 70 using a suitable combustion medium in gaseous form, such as natural or artificial gas. In this form of construction the heating means may comprise a jet or a plate having a plurality of jets 3, connected to a supply pipe 4 by means of a mixing chamber 15 and a casing 5, terminating at its upper end in an exhaust pipe 6. The casing 5 encloses a coil 7 connected at its opposite ends 75 with the tank 1, whereby the water therein may circulate through the coil 7, due to the heating of the water in the latter, and back to the tank and thus be stored therein in heated condition. 8 indicates a supply pipe 80 leading from the source of water supply and 9 indicates the discharge water pipe leading to any desired point. 10 indicates a supply pipe for the combustion medium, such as 85 gas, suitably connected to a hollow boss 11 extending from one side, preferably the upper side, of a casing 12, the purpose of which will be later set forth. 13 indicates a hollow boss arranged at another side (preferably the lower side) of the casing 12 and having connected to it a pipe 14 which is 90 connected to the pipe 4.

The casing 12 houses an operating mechanism, indicated as an entirety at 16, for a valve mechanism 17. The operating mechanism is controlled automatically by a thermostat 18, which preferably extends through the wall of the tank 1 so as to be surrounded by the water therein, whereby its temperature will effect expansion and contraction of one or both of its elements to actuate the 100 operating mechanism (or certain elements thereof) in one direction or permit their movement in the opposite direction. The thermostat may comprise a tube 18^a formed of copper or other material having a rela- 110

tively high co-efficient of expansion and a rod 18^b formed of a material which is substantially incapable of expansion under the influence of heat. As shown, the outer end 5 of the tube 18^a fits within a sleeve 19 having a threaded collar fitting a screw threaded opening 20 formed in the wall of the tank 1. The inner end of the tube 18^a is connected to the head of a screw 21 which fits a 10 threaded opening in the inner end of the rod 18^b, thereby adjustably connecting the elements 18^a, 18^b, together. The outer end of the rod 18^b engages with the operating mechanism 16 to actuate it, when the temperature 15 of the water in the tank 1 falls due to cooling thereof or discharge of water through the pipe 9 (which lowering of temperature causes a contraction of the tube 18^a and movement of the rod 18^b toward the left 20 as viewed in Figs. 2 and 4).

The operating mechanism 16 for the valve mechanism 17 is preferably substantially similar to that disclosed in Letters Patent No. 1,479,083, dated January 1, 1924, and 25 granted to Howard I. Morris, for which purpose the casing 12 comprises a pair of sections 12^a, 12^b; the latter enclosing a magnet 16^a arranged to be swung about a pivot 16^b by a system of levers 16^c, one of which is 30 engaged by the outer end of the rod 18^b and the former enclosing a rocker 16^d pivotally mounted on a rod or shaft 16^e and constituting an armature for the magnet 16^a and a linkage 22 between the armature 16^d 35 and the valve element 17^a of the valve mechanism 17. The casing sections 12^a, 12^b, are shaped along their abutting edges for connection with each other in a gas tight manner, being preferably provided with flanges 40 23 secured together by cap screws 24. The casing section 12^a is shaped interiorly to form a conduit 25 leading from the boss 11, a chamber 26 for the armature 16^d and linkage, and merging into the boss 13, and an 45 opening 27 leading from the conduit 25 into the chamber 26, the opening 27 being provided with a ring forming a valve seat 17^b for the valve element 17^a. The linkage 22 preferably comprises an arm 22^a connected 50 to the armature 16^d and a rod 22^b pivotally connected to the arm 22^a, which rod may comprise the stem of the valve element 17^a. The wall of the casing section 12^b surrounding the valve seat 17^b may be shaped to 55 form a hollow boss 12^c to permit assembly of and access to the valve element 17^a. The opening in the boss may be closed by a removable plug 28. The boss 12^c may also support a strainer 29 to prevent grit and 60 foreign matter from flowing to the valve mechanism 17.

In Figs. 2 and 3, the elements 18^a, 18^b, of the thermostat and operating mechanism 16 are shown in the positions they occupy when 65 the temperature of the water is at or above

a predetermined degree according to the adjustment of a regulating means indicated as an entirety at 29^a, in which position the valve element 17^a is seated against its seat 17^b and shuts off the flow of the gas to the jets 3. If now the temperature of the water in the tank 1 (or that portion surrounding the element 18^a) drops below a certain degree of temperature, the rod 18^b will move toward the left, as viewed in Figs. 2 and 4, 70 which movement in turn will swing the outer end of the magnet 16^a upwardly; this latter movement will rock the armature 16^d and thus move the valve element 17^a upwardly or unseat it, whereupon the gas will 80 flow to the heating means 2 and be ignited by a pilot burner 30. The jets 3 will remain lighted until the temperature of the water in the tank 1 reaches the predetermined temperature, whereupon the thermostat element 85 18^b will move toward the right and permit the operating mechanism to return to its first position, and seating of the valve element 17^a due to its weight and that of its stem 22^b, supplemented by the pressure of 90 the gas.

31 indicates a pipe leading from some suitable point above the valve mechanism 17 to the pilot burner 30, being preferably connected to a nipple or pipe section 32 leading 95 through the boss 11.

33 indicates as an entirety a mechanism for locking the valve mechanism 17 in closed position in the event the pilot burner 30 goes out, either by accident, drop in pressure, or failure of, the supply of gas or otherwise; the purpose and object being (if the pilot is not burning and capable of igniting the jets 3 when the temperature of the water in the tank 1 falls to or below that point at which the thermostat 18 would cause an opening of the valve mechanism 17) to positively and in an automatic manner prevent the opening of the valve mechanism 17 and supply of gas to the heating means 2 if 105 for any reason the pilot fails to burn. Of the locking mechanism 33, 34 indicates a holding system for a suitable medium (gas or liquid) capable of readily expanding under the influence of heat, such medium 110 preferably consisting of a quantity of alcohol, which when heated to form vapor expands within the system. The holding system 34 comprises a casing 35 having a stationary wall 35^a and an expandible wall 115 35^b, a pipe or conduit 36 connected at one end to an opening formed in the wall 35^a and a well 37 to which the other end of the pipe 36 is connected. As shown in the drawings, the well 37 is filled with the expansion 120 medium, such as alcohol, and when heated (as will later be described) it will vaporize and thus cause pressure within the system and resulting expansion or extension of the wall 35^b. The wall 35^b preferably comprises 125 130

a shell formed from relatively thin sheet copper, its lower end being secured in a liquid or gas tight manner to the periphery of the wall 35^a and its upper end being closed by a cap 35^c. The wall of the shell is formed with annular corrugations 35^d which permit it to readily expand and contract. To support the casing 35, the casing section 12^a is shaped to provide an integrally connected tubular member 38 depending from its lower wall and communicating with the chamber 26 through an opening 38^a for a purpose which will later appear. The inner wall of the member 38 is screw threaded to removably receive a plug 39 upon which the casing 35 may be supported, the plug 39 being formed with an opening 39^a through which the pipe 36 extends. Due to the opening 38^a leading from the chamber 26 into the tubular member 38, the plug 39 is arranged to fit the latter in a gas-tight manner. In the preferred form of construction, the upper end of the pipe 36 extends into and has screw threaded connection in the opening 39^a and the wall 35^a has a depending nipple 40 which is screw threaded into the opening 39^a to complete the liquid connection for the pipe 36; the arrangement serving to rigidly support the wall 35^a upon and connect it to the plug 39 and insuring the positive and ready removal of the casing 35 upon the removal of the plug 39. 40^a indicates a link having on its lower end a head 41 preferably secured to the cap 35^c and movable upwardly and downwardly therewith. The link 40^a extends upwardly through the opening 38^a and carries at its upper end a hook 42. The hook 42 extends over the arm 22^a to form an operative connection therewith, (a) permitting free movement of the arm 22^a and valve element 17^a so long as the casing 35 is expanded under the expansion influence of the medium within the holding system or (b) to lock the arm 22^a in its lower position (as shown in Fig. 2) and through it and the stem 22^b lock the valve element 17^a in seating position, when the casing 35 contracts due to the cooling or fall in temperature of the medium within the holding system 34. The contraction of the casing 35, following the cooling of the medium within its walls, is preferably insured by the provision of a coiled spring 35' arranged between the cap 35^c and the casing wall in which the opening 38^a is formed.

43 indicates a device disposed adjacent the pilot burner 30 in position for the flame jet or jets from the burner to lap its exposed face and thus heat it. The device 43 preferably comprises a wall of annular shape surrounding the pilot burner 30 so as to lap or be in position for the pilot jet or jets to contact therewith over a relatively wide area, whereby the wall is heated and remains heated so long as the pilot 30 burns. The wall 43 is preferably formed integrally with the walls forming the well 37, whereby the heat absorbed by the wall 43 will be conducted directly to the well to transmit it to the medium therewithin.

In the preferred form of construction we provide a cylinder 44 having end walls 44^a, 44^b, and an intermediate transverse wall 44^c forming between the end walls two chambers, the inner one constituting the well 37 and the outer one 37' forming a gas chamber for the pilot 30 which is mounted in an axial opening formed in the end wall 44^b, the pipe 31 extending through the wall of the cylinder 44 into the chamber 37'. In this form of construction the flame lapping wall 43 is formed integrally with the end wall 44^b and cylinder 44 and extends entirely around the latter so as to be in position for the flame of the pilot jet to engage. The pilot jet 30 is preferably provided with a pair of ports extending from its lateral sides radially in opposite directions, whereby the flame jets will come together above the pilot and lap the exposed face of the wall 43 (see Fig. 5), so that no carbon will collect on and affect the flame ports or collect on the wall 43 adjacent thereto and form an insulation or coating that would prevent heating of the wall 43. 45 indicates openings formed in the outer portions of the wall 43 and serving to supply air to the flame from the pilot jets and tending to prevent the collection of carbon on the exposed face of the wall.

By providing a wall in position to be heated by the flame from the pilot jets and connecting this wall directly with the wall of the well for the expansion medium we are enabled to utilize to advantage and efficiently the heat of the pilot flame to effect vaporization of the expansion medium and thus through use of pressure within the holding system release the arm 22^a, whereby the valve mechanism 17 will be operated (opened and closed) due to the rise and fall of the temperature of the water in the tank 1 and we insure this result without danger of carbon collecting on or around the pilot burner 30 and affecting its continuous burning.

As already set forth, the thermostat 18, operating mechanism 16 and valve mechanism 17 are shown in Fig. 2 in the position to affect closing of the valve element 17^a. However, under normal working conditions, the pilot burner 30 will be lighted, and the heat thereof will be conducted by the heated wall 43 to and through the wall 44 and heat the medium (alcohol) in the chamber or well 37. As a result, the medium will be vaporized and effect expansion within the casing 35, thereby extending the latter, lifting the link 40^a to the position shown in Fig. 130

6. In the event the pilot burner 30 goes out (or is put out), the walls 43 and 44 will cool off and the vapor in the holding system will condense, following which the casting 35 will contract and move the hook 42 of the link 40^a downwardly into engagement with or into position to prevent upward movement of the arm 22^a and unseating the valve element 17^a. Accordingly, 10 when the water in the tank 1 cools to a point below that degree of temperature at which the thermostat 18 actuates the operating mechanism 16, movement of the magnet 16^a and levers 16^c will be ineffective to operate the armature 16^d and valve element 17^a.

46 is a cut-off of suitable construction disposed in the pipe 10 and operated by a handle 47.

20 To those skilled in the art to which our invention relates many changes in construction and widely differing embodiments and applications of the invention will suggest themselves without departing from the spirit 25 and scope thereof. Our disclosures and the description herein are purely illustrative and are not intended to be in any sense limiting.

What we claim is:

1. In apparatus of the class described, the 30 combination with a heating means having a supply pipe for its combustion medium, of a cut off valve in said supply pipe, a pilot burner for igniting said heating means, a thermostat mechanism operatively connected 35 with the valve element of said valve and having an element affected by said heating means, whereby said valve is automatically controlled, and expansible means having a device associated with and arranged when 40 said expansible means are in normal position to engage the valve element and lock it in closed position, but when said expansible means are expanded to abnormal position to disengage the valve element, said expansible 45 means having a portion disposed in the heat zone of said pilot burner so as to be heated thereby, whereby the expansible means are maintained in an abnormal position to permit free operation of the valve element.

50 2. An apparatus as claimed in claim 1 in which that portion of the expansible means heated by the pilot burner is provided with a vertically arranged wall disposed at one side of and surrounding the upper portion 55 of said pilot burner.

3. An apparatus as claimed in claim 1 in which that portion of the expansible means heated by the pilot burner is provided with a vertically arranged wall disposed at one 60 side of and surrounding the upper portion of said pilot burner and said wall is formed with an air supply opening.

4. In apparatus of the class described, the combination with a heating means having a supply pipe for its combustion medi-

um, of a valve mechanism for said pipe, a pilot burner, a thermostatic mechanism for controlling the valve element of said valve mechanism, an expansion means comprising a holding system for a fluid medium which is vaporized under the influence of heat, an operative connection between the expansible wall of said system and said valve element arranged to normally lock the latter in closed position, and a wall associated with 70 said pilot burner and arranged in position to be heated thereby and connected with a wall of said holding system, whereby the vaporization of the medium therein will cause expansion of said expansion medium 75 and maintain said operative connection in unlocking position.

5. An apparatus as claimed in claim 4 in which the operative connection comprises a link that extends into the casing for said 80 valve mechanism and carries a device to engage an element connected to its valve element.

6. An apparatus as claimed in claim 4 in which the holding system comprises a casing 90 having an expanding wall and a well connected thereto and the wall to be heated is connected to the wall of said well.

7. An apparatus as claimed in claim 4 in which the holding system comprises a casing 95 associated with said valve mechanism and having an expanding wall and a well associated with said pilot burner and connected to said casing and the wall to be heated is connected to the wall of said well. 100

8. In apparatus of the class described, the combination with a heating means having a supply pipe, of a valve mechanism for said pipe, a pilot burner for igniting said heating means, a thermostatic mechanism for 105 controlling the valve element of said valve mechanism, a housing for elements of said thermostatic mechanism having a tubular member, a casing within said tubular member having an expansion wall, a well for 110 holding a quantity of a fluid, said well being connected with said casing, a wall associated with said pilot burner and heated thereby and connected to the wall of said well, whereby the heat conducted to the fluid 115 therein will be vaporized, to cause the expansion of said expansion wall, and an operative connection between said expansion wall and a part connected to said valve element arranged to lock the latter closed when the 120 fluid in said well is below its vaporizing temperature.

9. An apparatus as claimed in claim 4 in which the holding system includes a cylinder having chambers at its opposite ends, 125 one chamber forming a well for the expansion medium and the other chamber forming a conduit for the combustion medium for said pilot burner mounted centrally in the adjacent end wall of the cylinder and 130

the wall to be heated is integral with said cylinder.

10. In apparatus of the class described, the combination with a tank for a fluid to be heated, a heating means and a pipe for supplying the combustion medium for said heating means, of a pilot pipe connected to said supply pipe and having a burner associated with said heating means, a single valve in 10 said supply pipe to cut off or permit flow of the combustion medium therethrough, a thermostat acted on by the fluid in said tank to automatically operate said valve, a conduit for an expansible fluid so arranged that 15 a portion of its wall is heated by said burner to effect vaporization of the fluid, an expansion wall actuated by the pressure due to vaporization of the expansible fluid, and a device operated by said expansion wall and 20 arranged to engage with and lock the valve element to its seat when the fluid in said conduit is below that temperature at which it vaporizes and to disengage therefrom when the fluid is in a vaporized state.

25 11. An apparatus as claimed in claim 10 in which the expansion wall comprises a corrugated shell connected to said conduit to receive the vapor and the head of said shell carries the device to effect engagement and 30 disengagement with said valve element.

12. In apparatus of the class described, the combination of a tank for a fluid, a heating means for heating the fluid in said tank, said means including a burner and a pilot 35 associated therewith, a pipe for supplying fuel to said burner and said pilot, a single valve in said pipe beyond the connection of the pilot therewith, a thermostat mechanism

for opening and closing said valve, an expansion means containing a fluid capable of 40 being vaporized under the influence of heat and having a well for the fluid arranged to be heated by said pilot, a device operatively connected to said expansion wall and said valve serving to lock said valve to its seat 45 when the fluid in said expansion means is at a temperature below that at which it vaporizes and to release said valve for normal operation under the control of said thermostat mechanism when the fluid is vaporized. 50

13. In apparatus of the class described, the combination with a fluid tank, heating means therefor, a thermostatically controlled valve for said heating means, a pilot for said heating means, and means for shutting off 55 supply of fuel to said heating means when the pilot is extinguished, said means having a holder for a vaporizing fluid, one wall of said holder being extended and disposed in position for lapping by the flame from said pilot.

14. In apparatus as claimed in claim 4 in which the holding system includes a chamber forming a well for the expansion medium and another chamber forming a fuel supply 65 for the pilot and the pilot projecting centrally from the end wall of the latter chamber and said end wall being extended in radial directions, whereby the flame from the pilot laps therewith to heat the expansion medium. 70

In testimony whereof, we have hereunto subscribed our names.

MLEY W. THOMAS.
PAUL H. HAMILTON.
